UNITED STATES PATENT OFFICE.

ARTHUR ALAN ASHWORTH, OF COFFEYVILLE, KANSAS.

STILL.

1,300,548.

Specification of Letters Patent. Patented Apr. 15, 1919.

Application filed March 2, 1918. Serial No. 220,024.

To all whom it may concern:

Be it known that I, ARTHUR ALAN ASHWORTH, a subject of the King of Great Britain, residing at Coffeyville, in the county of 5 Montgomery and State of Kansas, have invented certain new and useful Improvements in Stills, of which the following is a specification.

My invention relates to apparatus, adapted 10 to distil or crack heavy oils, while not necessarily restricted to this use.

An important object of the invention is to provide means for rotating the body of oil within a stationary tube, for providing a continuous annular coating of oil upon the inner surface of the tube, whereby the tube may be heated to a high temperature, without liability of the same being injured.

A further object of the invention is to provide means to rotate the body of oil, to throw the same outwardly by centrifugal force, to form the annular coating of the tube and at the same time serving as effective scraping means to remove all particles of carbon which 25 may tend to deposit upon the interior of the tube.

A further object of the invention is to provide apparatus of the above mentioned character, which is continuous in operation, the 30 body of oil feeding longitudinally through the tube, together with the distillate.

Other objects and advantages of the invention will be apparent during the course of the following description.

35 In the accompanying drawings forming a part of this specification and in which like numerals are employed to designate like parts throughout the same,

Figure 1 is a horizontal sectional view 40 taken on line 1—1 of Fig. 5, parts being shown in elevation,

Fig. 2 is a longitudinal vertical sectional view taken on line 2—2 of Fig. 1,

Fig. 3 is a similar view taken on line 3—3 45 of Fig. 1,

Fig. 4 is a similar view taken on line 4—4 of Fig. 1,

Fig. 5 is a transverse sectional view taken on line 5—5 of Fig. 1,

50 Fig. 6 is an end elevation of the distilling tube,

Fig. 7 is a transverse sectional view through the same, and

Fig. 8 is an enlarged side elevation of the 55 combined agitating and scraping means, parts in section.

In the drawings, wherein for the purpose of illustration is shown a preferred embodiment of my invention, the numeral 10 designates the casing of a furnace, as a whole. 60 This casing is provided with longitudinal partitions 11 and 12, serving to provide longitudinal chambers 13, 14 and 15, as shown. The chamber 13 is provided with a lateral extension 16, into which projects the outlet end 65 of an oil burner 17, of any well known or preferred construction. Connected with the burner 17 is an oil supply pipe 18 and a steam supply pipe 19, as shown. The flame and products of combustion from this burner 70 discharge into one end of the chamber 13, at a point preferably near the lower end of an inclined longitudinal floor or bottom 20, shown more clearly in Fig. 2. The inclined floor or bottom 20 extends upwardly toward 75 the opposite end of the chamber 13 and is adapted to conduct the products of combustion or heated gases through a transverse opening 21, leading into one end of the chamber 14. The function of the inclined 80 floor or bottom 20 is to provide means whereby the heated gases or products of combustion will act uniformly upon the heating tube, to be described, throughout its entire length. The products of combustion, at the 85 maximum temperature, are introduced near the lower end of the floor or bottom 20 and are thus removed from close proximity to the tube, but as these gases travel longitudinally through the chamber 13, and become 90 slightly lowered in temperature, they approach the tube, by traveling up the inclined floor or bottom 20. As above stated, the opening 21 leads into one end of the chamber 14, at the upper end of a floor or bottom 95 22. At the lower end of this floor or bottom, the partition 12 has an outlet opening 23, leading into the chamber 15, at the upper end of a floor or bottom 24, as shown. At its lower end, the chamber 15 has an outlet opening 25, leading into a stack 26, as shown.

The numeral 27 designates a stationary main tube, preferably horizontally arranged, and extending longitudinally through the upper portion of the chamber 13, as clearly 105 illustrated in Fig. 2. This tube is spaced a slight distance from the top 28 of the chamber 13 and is therefore adapted to be completely surrounded by the heated gases or products of combustion. Extending longitudinally through the main tube 27 is a preferably tubular shaft 29, arranged in concen-

tric relation thereto. At the left end, in Fig. 2, the tubular shaft 29 receives a plug 30, which is rigidly secured therein, and provided with a reduced cylindrical extension 31, rotatable within a cylindrical recess or pocket 32, formed in a head 33. This head is secured to a coacting annular head 34, rigidly attached to the tube 27 by any suitable means. The head 33 has a gas-tight union 10 with the tube 27. It is thus apparent that this end of the tubular shaft 29 is supported in a manner so that it is free to rotate. At the opposite end of the tube 27 is a head 35, rigidly secured to an annular head 36, fixed 15 to the tube 27. The head 35 forms a gas-tight union with the tube 27. The head 35 is equipped with a stuffing box 37 through which extends a driving shaft 38 having a pulley 39 rigidly secured thereto. This pulley may be rotated by any suitable means. The outer end of the shaft 38 is journaled within a bearing 40, which is secured to an upright 41. The inner end of the shaft 38 is provided with an enlarged head 42, projecting 25 into the tubular shaft 29, and rigidly secured thereto by any suitable means. This head serves to drive the tubular shaft. The tubular shaft 29 is rotated in the direction of the arrows, as illustrated in Figs. 2 and 6.

30 As more clearly shown in Figs. 7 and 8, the tubular shaft 29 carries radial rails or bars 43, secured to curved bars 44. The bars 44 conform to the curvature of the tubular shaft 29, contact therewith, and are clamped 35 to the tubular shaft by diagonal bolts 45, passing through openings in the bars 44 and the tube 29, as shown. The tubular shaft 29 and radial rails or bars 43 form a portion of combined agitating and scraping apparatus.

40 The numeral 46 designates scraping elements, as a whole, and each scraping element embodies a pair of blades 47, which are radially disposed with respect to the wall of the tube 27, and at substantially a right angle thereto. The outer faces 48 of the blades 47 are machined to fit the curvature of the tube 27, and provide scraping or cutting edges 49. Disposed at the opposite ends of the blades 47 are transverse bridges 50, preferably cast integral therewith. These bridges are provided centrally thereof with radial openings or slots 51, to receive the radial rails or bars 43. Attention is called to the fact that the openings or slots 51 are 55 slightly larger than the radial bars 43, and thereby permit of the restricted movement of the scraping elements with respect thereto, so that these scraping elements may readily conform to any slight irregularity 60 which may be present in the wall of the tube 27. As more clearly shown in Figs. 2 and 8, the scraping elements 46 are arranged in end to end relation, and contact with each other. At each end of the radial rails 43, 65 are transverse pins 52, extending through

openings therein, and arranged to contact with the end scraping elements, thereby preventing longitudinal displacement of the scraping elements. As the two sets of scraping elements are bodily rotated they are 70 thrown outwardly into proper contact with the tube 27 by centrifugal force.

As more clearly shown in Figs. 1, 3, 4 and 5, preheating tubes 53 and 54 extend longitudinally within the chambers 14 and 15 respectively. At the right end of the preheating tube 54 (see Fig. 4) is an oil supply pipe 55, connected therewith by means of a coupling 56. The pipe 55 leads to a pump (not shown). At the opposite end of the 80 preheating tube 54 (see Fig. 1) is a transverse pipe 57, connected therewith by a coupling 58. The pipe 57 is connected with the corresponding end of the preheating tube 53 by a coupling 58'. The opposite end 85 of the preheating tube 53 has connection with a transverse pipe 59, through the medium of a coupling 60. The pipe 59 has a cut off valve 61 connected therein, as shown. The pipe 59, as more clearly shown 90 in Fig. 2, passes through an opening 60' in the head 35, and discharges into the tube 27, to feed the heavy oil into the same.

Arranged near the opposite end of the tube 27 are vertical closed tanks 61 and 62. 95 The tank 62 has connection with a pipe 63, discharging therein. This pipe 63 (see Fig. 6) passes through an opening 64 formed in the head 33, and discharges into the tube 27 at a point near and spaced from the wall 100 of the tube. The opening 64 is also arranged beneath the center of the tube 27 but spaced a substantial distance above the lowermost portion thereof. The location of the opening 64 determines the maximum 105 level of the oil within the tube, when the combined agitating and scraping means is inactive, and also determines the thickness of the annular covering of oil, formed upon the inner surface of the tube 27, when the 110 combined scraping and agitating means is active. The location of the opening 64 is considered important. The head 33 is also provided with an opening 65, leading into the tube 27, at the lowermost portion thereof. The opening 65 receives a drain pipe 66, 115 equipped with a cut off valve 67.

At its upper end the tank 62 has connection with an outlet pipe 68, for the escape of the products of distillation, and this pipe 120 leads to a suitable condenser (not shown). At its lower end the tank 62 has connection with a pipe 69 having a cut off valve 70 connected therein. A second valve 71 is connected in the pipe 69. The pipe 69 leads to 125 a residue tank (not shown). Connected with the pipe 69 is a T-coupling 72, having connection with a pipe 73 leading to the tank 61. A pipe 74 also connects the upper ends of the tanks 61 and 62, and this pipe 130

has a cut off valve 75, connected therein. A pressure gage 76 is connected with the tank 61, as shown.

The operation of the apparatus is as follows:

The heavy oils to be distilled or cracked, or both, are fed through the pipe 55, from the pump, and passes through the preheating tubes 54 and 53, and discharges into the free end of the tube 27, at the right end thereof, in Fig. 2. Under working conditions, I preferably maintain the pressure in the tube 27 at approximately 80 to 90 pounds to the square inch. The oil burner 17 is now operating and the heated gases or products of combustion discharging into the chamber 13. When entering the chamber 13, these products of combustion or heated gases have a high temperature and the burner 17 is preferably operated so that the tube 27 is heated and maintained at a temperature of 800 to 850° F., thereby subjecting the oils therein to substantially the same temperature. While thus being heated, the combined scraping and agitating means including the scraping elements 64, are rotating in the direction of the arrow and preferably at a rate of 75 revolutions per minute, while this speed may be varied as found advantageous. It is however essential to rotate the combined scraping and agitating means at a suitably high speed, to cause the oil within the tube 27 to be thrown outwardly by centrifugal force and form an annular covering for the entire inner surface of the tube 27. This is highly important as it prevents overheating of portions of the tube, and the formation of carbon deposits. The scraping means, is thrown out by centrifugal force and properly contacts with the inner side of the tube 27, thereby removing all particles of deposited carbon. This deposited carbon, when removed, is more or less pulverized and be ones mixed with the heavy oils, or residue, contained within the tube 27. The products of distillation and the residue discharge together through the pipe 63. The products of distillation descend through the tank 62 and pass through the pipe 68 to the condenser while the residue is collected within the tank 62. It is thus apparent that the entire mass within the pipe 27, travels longitudinally thereof toward the discharge tank 62, and the extent of this travel is controlled by controlling the feed of the oil through the pipe 55. It is thus apparent that the process of distillation or cracking may be carried on continuously without stopping the apparatus to remove the residue or carbon deposit, as the carbon deposit, in a finely divided or pulverized condition, is held suspended in the residue, and discharges through the pipe 63, as above stated. When a sufficient amount of the residue has accumulated within the tank 62, the valve

70 is opened, and such residue being under pressure within the tank 62, to wit, 80 to 90 pounds to the square inch, is forced into the tank 61, which is at atmospheric pressure. After this operation, the valve 70 is closed 70 and the valve 71 may be opened, thus allowing the residue to pass by gravity or the like, to the residue tank. If it should be necessary to exert pressure upon the upper portion of the mass within the tank 61, to force 75 the same therethrough, pressure may be obtained by opening the valve 75.

It is to be understood that the form of my invention herewith shown and described is to be taken as a preferred example of the same, 80 and that various changes in the shape, size, and arrangement of parts may be resorted to without departing from the spirit of the invention or the scope of the subjoined claims.

Having thus described my invention, I 85 claim:—

1. In apparatus of the character described, a heating chamber, a stationary tube extending longitudinally therein, members connected with the opposite ends of the tube with one member provided with an outlet opening arranged near and spaced radially from the inner surface of the tube for defining the thickness of the annular coating of oil within the tube, means for introducing oil or the like into the opposite end portion of the tube, and rotatable means disposed within the stationary tube for rotating the oil at a suitable speed to cause the same to move outwardly by centrifugal force and form 100 the annular coating within the tube. 95

2. In apparatus of the character described, a heating chamber, a stationary tube extending longitudinally therein, members connected with the opposite ends of the tube with one member provided with an outlet opening arranged near and spaced radially from the inner surface of the tube for defining the thickness of an annular coating of oil or the like within the tube, means for introducing oil or the like into the opposite end portion of the tube, combined agitating and scraping elements disposed within the tube and adapted to impart a rotary motion to the oil, and means to rotate said elements 110 at a suitable speed to cause the oil to move outwardly by centrifugal force and form the annular coating. 115

3. In apparatus of the character described, a stationary tube, means for surrounding the tube with a heating medium, means for supplying oil into one end portion of the tube, a head connected with the opposite end portion of the tube and having an outlet opening arranged near and spaced radially from the side portion of the tube for a greater distance and spaced from the bottom portion of the tube, means for receiving material passing through the outlet opening, combined scraping and agitating 125 130

means arranged within the tube and adapted to impart a rotary movement to the oil, and means to rotate the combined scraping and agitating means toward the upper portion of the outlet opening and at a sufficiently high speed to form an annular coating of the oil within the tube.

4. In apparatus of the character described, an approximately horizontal heating tube, means to feed oil into one end portion thereof, means to heat the tube, a rotary combined scraping and agitating device arranged in the tube and adapted to be acted upon by centrifugal force to move outwardly in contact with the inner wall of the tube, means to rotate the device so that it revolves the oil at a suitable speed to form an annular coating of the same in the tube, and outlet means for the oil near the other end of the tube serving to define the thickness of the annular coating.

5. In apparatus of the character described, a relatively stationary tube, means to supply oil into the tube, means to rotate the oil so that it forms an annular coating within the tube, means for heating the tube, and means permanently open during the operation of the apparatus for withdrawing the residue and distillate from the tube at a point within the annular coating, said withdrawing means being arranged inwardly of and spaced radially from the inner surface of the stationary tube to define the thickness of the coating of oil within said stationary tube.

6. In apparatus of the character described, a relatively stationary tube, means to heat the tube, means to supply oil into one end portion of the tube, combined agitating and scraping means disposed within the tube, means to rotate the combined agitating and scraping means at a speed to cause the oil to form an annular coating within the tube, and means for withdrawing the residue and distillate from the opposite end portion of the tube at a point within the annular coating, said withdrawing means being arranged inwardly of and spaced from the inner surface of the stationary tube to define the thickness of the coating of oil within the stationary tube.

7. In apparatus of the character described, a relatively stationary tube having a substantial length, heads connected with the opposite ends of the tube, means for sup-

plying a heating medium to the exterior of the tube, a valve controlled oil feeding pipe leading into one end of the tube, an outlet pipe passing through the head at the opposite end of the tube and arranged inwardly of and near and spaced radially from the periphery of the tube for defining the thickness of the coating of oil within the tube, said outlet pipe remaining permanently open during the operation of the apparatus, a receiving apparatus connected with the outlet pipe, and a combined agitating and scraping device extending longitudinally within the tube and adapted to be rotated therein, said device being adapted to impart a rotary movement to the oil to form an annular coating within the tube.

8. In apparatus of the character described, a relatively stationary substantially horizontal tube having a substantial length, closing means connected with the opposite ends of the tube, a valve controlled oil feeding pipe leading into one end of the tube, an outlet pipe passing through the closing means at the opposite end of the tube and arranged inwardly of and near and spaced radially from the inner surface of the tube for defining the thickness of the coating of oil within the tube, said outlet pipe remaining permanently open during the operation of the apparatus, apparatus connected with the outlet pipe and adapted to separate the gaseous and liquid products passing through the outlet pipe, a rotatable agitating device extending longitudinally within the tube, said device being adapted to impart a rotary motion to the oil to form an annular covering within the tube, and means to heat the tube.

9. In apparatus of the character described, a heating tube, means to feed oil or the like into the tube, means to heat the tube, a rotary agitating device arranged in the tube, means to rotate the device so that it revolves the oil at a suitable speed to form an annular coating of the same in the tube, and outlet means for the oil serving to define the thickness of the annular coating.

In testimony whereof I affix my signature in presence of two witnesses.

ARTHUR ALAN ASHWORTH.
